UNITED STATES PATENT OFFICE

BASIL N. MACGREGOR, OF WARREN, OHIO, ASSIGNOR TO THE PACKARD ELECTRIC COMPANY, OF WARREN, OHIO, A CORPORATION OF OHIO

MERCHANTISE-DISPLAY APPARATUS

Application filed October 21, 1925. Serial No. 63,839.

This invention relates to merchandise display apparatus and more particularly to apparatus for displaying and dispensing flexible cords, cables, etc. It is one of the objects 5 of the invention to provide a simple form of apparatus, for the purpose specified, that may be inexpensively manufactured, that will be attractive in appearance and on which the merchandise may be systematically arranged 10 and convenient for dispensing desired lengths of any particular kind.

Other objects of the invention and the features of novelty will be apparent from the following description taken in connection 15 with the accompanying drawings, of which:

Fig. 1 is a perspective view of an apparatus embodying my invention;

Fig. 2 is a longitudinal section thereof; and

Fig. 3 is a horizontal section on the line 3—3 of Fig. 2.

Referring to the drawings, 10 indicates a sheet metal panel having integral rearwardly extending marginal flanges 11 and hooks 12 struck-up from the metal of the panel and projecting forwardly from the face thereof. The hooks 12 are arranged in pairs and in horizontal rows, as shown in Fig. 1 and support wire frames or hangers 13, preferably of 20 rectangular form, as shown, and having aligned pivots 14 on which spools 15 are rotatably arranged. Each of the spools 15 is adapted to carry a supply of cord, flexible cable or similar merchandise and this cord or cable may be conveniently withdrawn from the spools, as desired, the spools resting against the face of the panel and such engagement with the panel serving as a brake 25 to offer a certain amount of resistance to the rotation of the spools and prevent more than the desired quantity of merchandise from being unwound therefrom.

The apparatus as thus described and illustrated is attractive in appearance and the spools 15 provide a convenient means for storing and dispensing the merchandise. When it is desired to change a spool, the side members of the frames 13 may be sprung 30 apart to disengage the pivots 14, thereby per-

mitting the removal of a spool and the insertion of another spool.

Having thus described my invention, I claim:

In apparatus of the class described, the 55 combination of a sheet metal panel having hooks on the face thereof struck-up from the metal thereof and arranged in pairs, said panel having marginal rearwardly extending flanges, hangers arranged on the respective 60 pairs of said hooks and comprising horizontally extending pivots, and spools rotatably arranged on said pivots with the flanges of 65 said spools in frictional engagement with the face of said panel.

In testimony whereof, I hereunto affix my signature.

BASIL N. MACGREGOR.
